(57) **CLAIM**

The ornamental design for an image capture device, as shown and described.

DESCRIPTION

FIG. 1 is a back elevation view of a first embodiment of an image capture device showing the new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a back elevation view of a second embodiment of an image capture device showing the new design;

FIG. 8 is a front elevation view thereof;

FIG. 9 is a left side elevation view thereof;

FIG. 10 is a right side elevation view thereof;

FIG. 11 is a top plan view thereof; and,

FIG. 12 is a bottom plan view thereof.
